(57) **CLAIM**

The ornamental design for a wireless headset, as shown and described.

DESCRIPTION

1. Wireless headset

1.1 is a front perspective view of a wireless headset showing our new design;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof; and

1.8 is a left side elevation view thereof shown in use.

The broken line showing portions of the wireless headset and environmental user form no part of the claimed design.
